DESIGN FOR A CONCRETE VIBRATOR

Forrest G. Douglass, Los Angeles, Calif., assignor
to Viber Company Limited, a corporation of
Nevada

Application March 13, 1935, Serial No. 55,871

Term of patent 14 years

To all whom it may concern:

Be it known that I, Forrest G. Douglass, a citizen of the United States, residing at Los Angeles, in the county of Los Angeles and State of California, have invented a new, original, and ornamental Design for Concrete Vibrators, of which the following is a specification, reference being had to the accompanying drawing, forming a part thereof.

Fig. 1 is a perspective view of a concrete vibrator embodying my design.

Fig. 2 is a side elevation of the same with a portion of the handle broken away for convenience in illustration.

I claim:

The ornamental design for a concrete vibrator, as shown.

FORREST G. DOUGLASS.
